UNITED STATES PATENT OFFICE.

CHARLES N. BLACK, OF NEW HAVEN, CONNECTICUT.

CONSTANT-CURRENT DYNAMO.

SPECIFICATION forming part of Letters Patent No. 593,388, dated November 9, 1897.

Application filed February 1, 1897. Serial No. 621,397. (No model.)

To all whom it may concern:

Be it known that I, CHARLES N. BLACK, of New Haven, in the county of New Haven and State of Connecticut, have invented a new Improvement in Constant-Current Arc-DYNAMOS; and I do hereby declare the following, when taken in connection with the accompanying drawing and the letters of reference marked thereon, to be a full, clear, and exact description of the same, and which said drawing constitutes part of this specification, and represents a diagrammatic view of a two-pole eight-bobbin machine having its internal connections arranged in accordance with my invention.

My invention relates to an improvement in constant-current arc-dYNAMOS, the object being to produce a dynamo having its internal and external circuits arranged so as to distribute the potential in such a manner as to keep it within safe working limits, whereby an increase in lamp capacity is secured without a necessary increase in voltage between any two points in the system. My invention is particularly designed to be used in the construction of large machines.

With these ends in view my invention consists in the connection of the terminals of the individual bobbins or sets of bobbins of an open-coil constant-current dynamo to segments of different commutator-rings.

My invention further consists in certain details of arrangement, as will be hereinafter described, and pointed out in the claims.

The accompanying drawing is a diagrammatic representation of the application of my invention to a constant-current open-coil arc-dynamo. The armature-core I has bobbins A A', B B', C C', and D D' wound upon it.

Each of these bobbins is connected to the diametrically opposite bobbin, but is entirely distinct from all of the other bobbins and has no electrical connection with them except through the brushes X X' Y Y' and

through the outside lamp-circuits L and L'. The bobbin A' is shown as wound upon the outside or top of the bobbin A, the bobbin B' upon the outside or top of the bobbin B, the bobbin C' upon the bobbin C, and the bobbin D' upon the bobbin D, but this is not essential, for, if preferred, the bobbin A' might be located at the side instead of on top of the

bobbins A, and so on with the other bobbins. If the bobbins are located side by side, as just suggested, it may be found necessary to adjust the brushes either forward or backward slightly in order to equalize the sparking. Such an adjustment may also be necessary, even when the bobbins are superposed, as shown in the drawing, to compensate, as it were, for inequalities in the construction or in the materials employed. The commutator-segments to which the various bobbins are connected are designated by a a', b b', c c', and d d'. The brushes X and Y and X' and Y' bear upon these segments. The field-magnets F and F' are located in the lamp-circuits L and L', before mentioned. Each of the said lamp-circuits is represented with five lamps in it, these being represented in the conventional way by crosses. Of course the number of lamps may be varied as desired, and it is not necessary that there should be the same number in each circuit. The connections of the bobbins C and C' and the bobbins D and D' to their proper commutator-segments c c' and d d', respectively, are for convenience omitted, but it may be understood that the said connections are identical in arrangement with the connections shown between the bobbins A A' and the commutator-segments a a' and the connections between the bobbins B B' and the commutator-segments b b'. The commutator-segments a', b, c', and d form one ring of the commutator, while the commutator-segments a, b', c, and d' form the other ring of the commutator. The bobbin A is connected through the wire o to the commutator-segment of the outer ring and also through the wire p, the bobbin B, and the wire q to the opposite commutator-segment b of the inner commutator-ring. The bobbin A' is connected by the wire n to the commutator-segment a' of the inner ring and also connected by means of the wire m, the bobbin B', and the wire r to the commutator-segment b' of the outer commutator-ring. The bobbin B is connected by the wire q directly to the commutator-segment b of the inner commutator-ring and also connected through the wire p, the bobbin A, and the wire o with the commutator-segment a of the outer commutator-ring. The bobbin B' is connected by the wire r directly to the

commutator-segment b' of the outer commutator-ring, and through the wire m , the bobbin A' , and the wire n to the outer segment a' of the inner commutator-ring. The connection of the bobbins C and C' and D and D' are identical in arrangement with the connections just described for the bobbins A and A' and B and B' , but are omitted so as to avoid the confusion which would result from multiplying the wires.

It will thus be observed that under my improved arrangement the respective bobbins of the machine are connected to opposite segments of different and distinct commutator-rings instead of to opposite segments of the same commutator-ring, as has been done heretofore. Thus the bobbins A and B are electrically connected not to opposite segments of the same commutator-ring, but to opposite segments of different and distinct commutator-rings. The same is true of all the other bobbins. Here I may remark that heretofore in machines of this type each commutator-segment has always had an "angular displacement" with respect to all of the other commutator-segments of the same pair of rings.

By the term "angular displacement" I mean to describe the arrangement which has heretofore obtained and under which the ends of all of the commutator-segments have been dodged or placed out of alignment.

Under my invention, as will be observed by reference to the drawing, the ends of the complementary commutator-segments are directly opposite and coincident and intersected by a radial plane emanating from the center of the armature-shaft. Thus the commutator-segments a and a' of the outer and inner commutator-rings, respectively, are complementary and have their ends directly opposite each other and coincident and in position to be intersected by a radial plane emanating from the center of the armature-shaft.

The machine shown has two rings, but if this number were increased, say, to four rings then the commutator-segments of the second pair of rings would have an angular displacement with respect to the commutator-segments of the first pair of rings, but the segments of the respective pairs of rings would have no angular displacement with respect to each other, and so on.

I have already pointed out that in my improved machine the complementary segments of each pair of rings have no angular displacement with respect to each other. I should also point out that in my improved machine the brushes of corresponding sign are also arranged substantially without angular displacement. I say "substantially without angular displacement" because they may be slightly staggered or deflected with respect to each other in adjusting them either forward or backward to equalize the sparking and compensate for imperfections of construction and inequalities of material; but

the positive brushes X and Y (shown in the drawing) have no angular displacement with respect to each other; no more have the negative brushes X' and Y' .

Having now described the arrangement of the connections in the machine chosen for illustration I will proceed to trace the path of the current. Starting at any point—such, for instance, as the brush X , which is the positive brush—the current passes in the direction of the arrow, around the field-magnets F and F' , through the lamp-circuit L' , to the negative brush X' . Here the current divides, a part of it passing to the segment b' and a part to the segment d' , with which the said brush is engaged when the commutator-rings are in the positions in which their segments are shown by the drawing. That portion of the current entering the commutator-segment b' passes thence through the connecting-wire r to the bobbin B' , through the wire of this bobbin and out through the connecting-wire m to the bobbin A' , thence through the wire n of this bobbin and out through the connecting-wire n , and thence to the commutator-segment a' of the inner commutator-ring, from which the current passes to the positive brush Y , in which it joins with the other part of the current. That portion of the current entering the segment d' flows through a connecting-wire (not shown) to the bobbin D' and around the same, and thence through a connecting-wire (not shown) to the bobbin C' , thence through a connecting-wire (not shown) to the commutator-segment c' , on which the positive brush Y also bears. The connecting-wires referred to, but not shown, correspond to the connecting-wires of the bobbins A' and B' and will be understood by reference thereto. From the positive brush Y the current passes through the lamp-circuit L to the negative brush Y' . Here the current again divides, a portion of it passing to the segment b of the inner commutator-ring and a portion to the segment d of the same ring. From the commutator-segment b the current passes through the connecting-wire q to the bobbin B and around the same, and out through the connecting-wire p , which leads it to the bobbin A , which it passes around, and out into the connecting-wire o , and thence to the commutator-segments a of the outer commutator-ring upon which the positive brush X bears. At this point the current joins the other portion of the same current, which divided, as mentioned, at the negative brush Y' . The said other portion of the current flows to the segment d , thence through a connecting-wire (not shown) to the bobbin D and around the same, and out through a connecting-wire (not shown) to the bobbin C and around the same, and through a connecting-wire (not shown) to the commutator-segment c of the outer commutator-ring, and thence to the brush X . I may remark here that as in all machines of this type the current does not divide, as described above, at certain points in the revo-

lution of the armature, but follows a single path—as, for example, when the brushes are bearing only upon the segments *c* and *c'* and *d* and *d'*.

5 I have used a two-pole eight-bobbin machine to illustrate my invention, but it is equally applicable to a multipolar machine with a larger number of bobbins. If desired, one of the field-magnets may be included in 10 one lamp-circuit and the other field-magnet in the other lamp-circuit, this principle being applicable in any machine constructed under my invention without regard to size.

I may call attention to the fact that the 15 external connections of my improved machine are like the external connections of machines known to the art as the "old Brush" machines.

It is a peculiarity of a machine connected 20 up in accordance with my invention that the lamps and field-circuits are interposed between the segments of the same commutator-ring.

I wish it understood from the foregoing 25 modifications suggested and of others that may obviously be made that I do not limit myself to the exact arrangement therein shown and described, but hold myself at liberty to make such changes and alterations as fairly 30 fall within the spirit and scope of my invention.

Having fully described my invention, what I claim as new, and desire to secure by Letters Patent, is—

35 1. An open-coil, constant-current dynamo, having the terminals of its individual bobbins or sets of connected bobbins connected to segments of different commutator-rings.

2. An open-coil, constant-current dynamo, 40 having the complementary segments of each pair of its commutator-rings arranged without angular displacement with respect to each other, and also having its brushes arranged

substantially without angular displacement so far as the brushes bearing upon the complementary segments of any two pairs of commutator-rings are concerned. 45

3. An open-coil, constant-current arc-dynamo, having the terminals of its individual bobbins or sets of connected bobbins connected to opposite segments of different and distinct commutator-rings, the complementary segments of which have no angular displacement with respect to each other. 50

4. An open-coil, constant-current arc-dynamo, having two or more generating-bobbins or sets of bobbins, and having its internal connections arranged for the interposition of lamp and field circuits between the brushes bearing upon the segments of the same ring. 55

5. An open-coil, constant-current arc-dynamo having the terminals of its individual bobbins or sets of connected bobbins connected to opposite segments of different and distinct commutator-rings, and its lamp-circuits connected between brushes bearing on 60 sections of the same ring. 65

6. A method of connecting two or more lamp-circuits with an open-coil constant-current dynamo, the said method consisting in 70 interposing the several bobbins or sets of bobbins between separate and distinct commutator-rings, and in interposing the lamp and field circuits between brushes bearing on segments of the same ring, whereby increase 75 in lamp capacity is secured without any necessary increase in voltage between any two points in the system.

In testimony whereof I have signed this specification in the presence of two subscribing witnesses. 80
